United States Patent [19]

Hasegawa et al.

[11] Patent Number: Des. 317,300

[45] Date of Patent: ** Jun. 4, 1991

[54] SEMI-CONDUCTOR MOUNTING SUBSTRATE

[76] Inventors: Terutomi Hasegawa, 2-40 Nakagawa-Cho, Ogaki-City, Gifu pref.; Nobumichi Goto, 291, Kami-Shirokane, Seki City Gifu Pref, both of Japan

[*] Notice: The portion of the term of this patent subsequent to May 14, 2005 has been disclaimed.

[**] Term: 14 Years

[21] Appl. No.: 140,433

[22] Filed: Jan. 4, 1988

CLAIM

The ornamental design for a semi-conductor mounting substrate, as shown.

DESCRIPTION

FIG. 1 is a top perspective view of a semi-conductor mounting substrate showing our new design; FIG. 2 is a bottom perspective view thereof; FIG. 3 is a right side elevational view thereof; FIG. 4 is a left side elevational view thereof; FIG. 5 is a rear elevational view thereof; and FIG. 6 is a front elevational view thereof.

FIG. 1

FIG. 2

FIG. 3

FIG. 4

FIG. 5

FIG. 6
